UNITED STATES PATENT OFFICE

151,745

DESIGN FOR A SWEATER OR SIMILAR ARTICLE

Bernard Ehrenreich, New York, N. Y.

Application March 17, 1948, Serial No. 145,183

Term of patent 3½ years

(Cl. D3—4)

To all whom it may concern:

Be it known that I, Bernard Ehrenreich, a citizen of the United States of America, residing in New York, county of New York, and State of New York, have invented a new, original, and ornamental Design for a Sweater or Similar Article, of which the following is a specification, reference being had to the accompanying drawing, forming part thereof.

Fig. 1 is a front view of a sweater or similar article, showing my new design.

Fig. 2 is a rear view thereof.

The essential features of my design reside in the portions shown in full lines on the drawing.

I claim:

The ornamental design for a sweater or similar article, substantially as shown and described.

BERNARD EHRENREICH.
